UNITED STATES PATENT OFFICE.

WILLIAM B. FENN, OF COLUMBUS, OHIO, ASSIGNOR TO THE WEDOIT COMPANY, OF COLUMBUS, OHIO, A CORPORATION OF OHIO.

TREATING-CHAMBER FOR STERILIZING-MACHINES.

1,141,241.

Specification of Letters Patent.

Patented June 1, 1915.

Application filed November 22, 1910. Serial No. 593,634.

To all whom it may concern:

Be it known that I, WILLIAM B. FENN, a citizen of the United States, residing at Columbus, in the county of Franklin and State 5 of Ohio, have invented a certain new and useful Improvement in Treating-Chambers for Sterilizing-Machines, of which the following is a specification.

The object of this invention is to provide 10 an improved form of device for treating—sterilizing for example—a material in a vessel.

The invention is embodied in the example 15 of it shown in the accompanying drawing and set forth in the following description, the features of novelty being pointed out in the claim appended to the description.

In the said drawing—Figure 1 is a horizontal section on the line $x-x$ Fig. 2 and 20 Fig. 2 is generally a vertical section of the device on the line $y-y$ Fig. 1. Fig. 3 is a detail partly in section showing the treating head depressed.

In the views 3 designates a cylindrical 25 chamber having on its side at its lower portion an opening 3^a sufficiently large to admit the can or container of the products to be treated. Suitably hinged to the exterior of the chamber as at 4 is a door 5 adapted to 30 close the opening 3^a and to insure tightness of the closure there can be provided a packing 6. The inner side of the door 5 at its lower portion has projecting from it a shelf or support 7 adapted to receive the aforesaid 35 can or container, an example of which is shown and designated 8.

In the upper portion of the chamber 3 is a piston 9 and below this piston a head 10 the two being connected but separated by a 40 space 11. The head 10 is furnished with a nozzle 12 preferably perforated to discharge sterilizing material laterally. The sterilizing head and nozzle can be of any suitable construction, such sterilizing head not in its 45 details constituting a part of the present invention. The chamber 3 has connected with it a pipe 13 for admitting fluid pressure to depress the piston and treating head. When the sterilizing head is properly depressed it 50 closes the upper end of the can which is left

open and the nozzle penetrates the material in the can as shown in Fig. 3.

14 designates a pipe connected with the chamber to admit the treating material. The discharge end of this pipe is located so 55 that when the sterilizing head is depressed the treating agent is admitted to the space 11 between the piston and the head from which the sterilizing agent passes through the duct 10^a in the head to the treating 60 nozzle.

15 designates a pipe connected with the lower portion of the chamber to admit pressure around the exterior of the can and prevent it from bursting if the pressure of the 65 sterilizing agent be greater than can be withstood by the can.

Where the sterilizing chambers are arranged in a moving circular series it is important that some means be provided for 70 holding the doors closed. The means shown for this purpose consists of a stationary rail 16 having a beveled end 16^a and a roller 17 mounted on a bearing which can be the shank of a bolt 18 secured on ears 19 on the 75 outer side of the door 5. When the moving chamber containing the can approaching the rail contacts with the beveled end 16^a the door is given a closing movement and is finally tightly closed by the inner side of 80 the rail.

The forms of the parts can be varied without departing from the gist of the invention.

What I claim is:

1. In a sterilizing machine, the combination of a chamber having an opening for the insertion of a vessel, and means in the chamber for applying a sterilizing agent to a vessel in said chamber, a door for said opening, and a shelf on said door to receive the vessel. 85

2. In a sterilizing machine, the combination of a chamber, having an opening in its upright side for the insertion of a vessel, and means in the chamber for applying a sterilizing agent to a vessel in said chamber, 95 a door for the said opening and a shelf on said door to receive the vessel.

3. In a sterilizing machine, the combination of a chamber having an opening for the insertion of a vessel, and means in the cham- 100

ber for applying a sterilizing agent to a vessel in said chamber, a door for said opening and means whereby said door may be automatically closed when the chamber is moved 5 toward the same.

4. In a sterilizing machine, the combination of a movable chamber having an opening for the insertion of a vessel, means in the chamber for applying a sterilizing agent to

a vessel in said chamber, a door for said 10 opening and means consisting of a rail toward which the door may be moved to close the same, substantially as described.

WILLIAM B. FENN.
